YARN PACKAGE SUPPORT

Thomas K. Rea, Gastonia, N. C., assignor to
Cocker Machine and Foundry Company, Gastonia, N. C., a corporation of North Carolina

Application March 10, 1949, Serial No. 80,693

5 Claims. (Cl. 242—130)

1

This invention relates to yarn package supports, and is concerned more specifically with supports designed for axially hollow yarn packages useful in connection with creels from which multiple yarns are drawn, as in warp beaming operations and the like.

The aim of my invention is to provide a support for the stated purpose which is of simple and inexpensive construction; to which the yarn packages can be easily and quickly applied and from which they can be as readily removed; which will permit quick change over from packages of coned configuration to packages of cylindric configuration without requiring special adapters as was ordinarily the case heretofore; and which will permit complete rotations of the package in taking up the slack after the leading end of one package is tied by the creel attendant, to the trailing end of a package on an associated holder in the creel, for maintenance of a continuing supply of the yarn.

In the attached drawings, Fig. 1 is a fragmentary view, partly in longitudinal section, of a creel provided with one of my improved yarn package supports.

Fig. 2 is a transverse section taken as indicated by the angled arrows II—II in Fig. 1.

Fig. 3 is a view like Fig. 1, showing an axially hollow frusto-conical yarn package in place on the support.

Fig. 4 is another elevational view of the creel with two of my improved yarn package supports associated to provide a continuing supply of the yarn; and

Fig. 5 is a view, in turn like Fig. 3, showing the support arranged for the mounting of a cylindric yarn package.

Referring first more particularly to Figs. 1 and 2 of these illustrations, it will be observed that my improved yarn package support comprises an arm 10 with a vertical axis fulcrum hub 11 adapted to fit freely about a post 12 of the creel. At the bottom, the hub 11 has radial lugs 13 which normally engage radial V notches 14 in the top of a collar 15 fast on the post 12, so that the arm 10 is releasably held in a definite position circumferentially of said post. Extending at a slight upward inclination to the horizontal from a boss 16 at the distal end of arm 10, is a round ended stem 17, and upstanding from said boss at right angles to said stem is a projection 18 with forwardly projecting brush bristles 19 adjacent the top thereof.

Rotatable about the stem 17 is a holder 20 which is adapted to receive and frictionally re-

2

tain a frusto-conical yarn package P (Fig. 3) having an axially-hollow core C. As shown, the holder 20 comprises a collar 21 which is bored to slide freely over the stem 17, and from which radiate, at circumferential intervals, a plurality of longitudinally-elongate straight-sided friction loops 22. These loops 22 extend to substantially equal distances beyond opposite faces of the collar 21, each being formed from a single length of stout spring wire with a coil 22a at one end for more effective resistance to easy flexure, and the terminals of the wire being aligned to meet centrally of the inner side portion of the loop within a longitudinal groove 23 at the periphery of said collar. For the purpose of securing the loops 22, the metal of the collar 21 is displaced inwardly from the opposite side walls of the grooves 23 as at 24 in Fig. 1, over the terminals of the wire.

Lodged within a straight-bottomed transverse slot 25 in collar 21 is a keeper latch 26 fashioned to hair pin configuration, see Fig. 2, likewise from spring wire. As shown, the arm 26a of the latch 26 is engaged, as at 27, with one end of the wire of one of the loops 22 bridging the slot 25, while its other arm 26b normally rests in a circumferential groove 28 in the stem 17, the free end of the latter arm being retroverted as at 26c so that it can be readily grasped and lifted, against spring action, from said groove when the holder 20 is to be removed. By virtue of the arrangement just described, the holder 20 is prevented from shifting axially from a definite location on the stem 17.

In the use of the support, the yarn package P is forced over the holder 20 to the position shown in Fig. 2, incident to which the spring loops 22 yield to compression, and, as a consequence, thereafter frictionally hold the package in place with the bottom end thereof bearing against the brush 19 for restraint against free rotation as the yarn is drawn from it.

In practice, the supports of my invention are made as rights and lefts and intended for association in pairs as shown in Fig. 4, with the arms 10 and 10' so positioned on the creel posts 12 and 12', that the axes of the stems 17, 17' are radial to a guide 30 through which the yarn is passed en route to the beam of the warper (not illustrated) with which the creel is employed. With this set up, the trailing end of the yarn Y of the package P is tied to the leading end of the yarn Y' of the reserve package P'. Upon exhaustion of the package P, it is replaced by a new package, and the leading end of the latter tied to the trailing end of the yarn of package

P'. In this way a continuing supply is maintained for beaming in a manner well known in the art. However, with my improved support, it is possible to turn the holder upon which the new package is placed, fully about the stem, against the resistance imposed by the brush 19, to take up the slack in the yarn after the leading end thereof has been tied to the trailing end of the package from which the yarn is being drawn at the time.

A further advantage of my improved support is the facility with which the holder 20 can be removed from the stem 17 upon retraction of the keeper latch 26, so that it may be used in supporting a cylindric yarn package P2, as shown in Fig. 5, whereof the core C2 fits the stem 17. Due to rounding of the end of stem 17, the holder can be easily replaced, incident to which the latch 26 will automatically seek its place within the circumferential groove 28 in the stem.

I claim:

1. In a support for axially hollow yarn packages; a mounting stem; and a package holder comprising a collar rotatively engaged on the stem, a plurality of straight-sided radially-arranged elongate spring loops at intervals circumferentially of the collar aligned in the direction of the stem and extending in opposite directions beyond the collar to substantially equal extents, said loops converging toward the outer end of the stem and having the capacity to yield to compression as the yarn package is slipped into place over the holder.

2. A yarn package support according to claim 1, in which each spring loop is formed from a single length of wire with the terminals thereof anchored within a longitudinal groove in the periphery of the collar.

3. A yarn package support according to claim 1, further including a releasable latch means for preventing axial shifting of the holder along the stem.

4. A yarn package holder according to claim 1, further including a retractable spring keeper latch on the collar adapted to engage a circumferential groove in the stud and thereby prevent shifting of the holder axially of the stem.

5. A yarn package support according to claim 1, wherein the collar is provided with a transverse slot, and further including a spring keeper latch of hairpin configuration lodged in said slot, one arm of said latch having its end engaged with the inner anchored side of one of the loops overlying the slot, and its other arm lying against the bottom of the slot while normally engaging a circumferential groove in the stem, and said other arm having its end projecting beyond the collar for convenience of manipulation in withdrawing said last mentioned arm from said groove when it is desired to remove the holder from the stem.
